[57] CLAIM

The ornamental design for "bezel ring for analog wristwatch", as shown and described.

DESCRIPTION

FIG. 1 is a top plan view of my improved bezel ring for an analog wristwatch;

FIG. 2 is a right side elevational view thereof;

FIG. 3 is a left side elevational view thereof;

FIG. 4 is a front end elevational view thereof;

FIG. 5 is a rear end elevational view thereof; and,

FIG. 6 is a bottom plan view thereof.

The broken-line showings of the watchcase and band portions are environmental only and form no part of the claimed design.
